Patented Oct. 31, 1911.

COLUMBIA PLANOGRAPH CO., WASHINGTON, D. C.

UNITED STATES PATENT OFFICE.

ARTHUR S. DURRUM, OF DAYTON, TERRITORY OF NEW MEXICO.

MATCH-SAFE.

1,007,547.

Specification of Letters Patent. Patented Oct. 31, 1911.

Application filed October 12, 1910. Serial No. 586,641.

To all whom it may concern:

Be it known that I, ARTHUR S. DURRUM, citizen of the United States, residing at Dayton, in the county of Eddy and Territory of New Mexico, have invented certain new and useful Improvements in Match-Safes, of which the following is a specification.

This invention relates to improvements in match safes, wherein a single match may be extracted without disturbing the remaining matches in the safe, and has for one of its objects to improve the construction and increase efficiency and utility in devices of this character.

With this and other objects in view the invention consists in certain novel features of construction hereinafter described and then specifically pointed out in the claim; and, the drawings illustrative of the preferred embodiment of the invention.

Figure 1 is a view of the blank from which the safe is constructed. Fig. 2 is a perspective view from the rear and from beneath of the improved device in operative position. Fig. 3 is a vertical section on the line 3—3 of Fig. 2.

The improved device is constructed wholly of sheet metal, and comprises three portions, the body which is constructed from a single piece of sheet metal, bent to the required shape, a cover for the body hingedly connected thereto, and a follower member located within the body and bearing constantly upon the matches therein, and serving as a weight to keep the body of matches pressed downwardly so that the lowermost match will always be retained in position for ready removal.

In Fig. 1 is shown the blank from which the body is constructed and comprises the front portion 10, back portion 11, and the end portions 12—13, the back 11 having an extension 14 along one side. Extending from the lower end of the back 11 is the bottom member 15, the latter having side recesses 16—17 and with a notch 18 in its outer edge as shown. The front 10 is longer than the back 11 and the lower ends of the sides 12—13 are formed oblique to the lon-

gitudinal plane of the side, so that when the parts are folded along the dotted lines 19 a rectangular structure is produced with the lower ends of the sides inclined. Extending from the end 13 are a plurality of tongues 20, which fit through corresponding slits 21 at the juncture of the back 11 and the extension 14, so that when the parts are folded together the tongues 20 are inserted through the slits 21 and bent over the back 11, and thus unite the parts. Projecting from the inclined end of the side 12 is a flap-like member 22 having inclined edges and corresponding to and fitting within the recess 17 of the bottom 15, while a similar flap 23 projects from the bottom inclined edge of the side 13 and corresponds to and fits in the recess 16 of the bottom 15, so that when the parts 10—11—12—13 are folded into oblong form and secured by the tongues 20 and the bottom 15 and the flaps 22—23 are folded together, the bottom of the structure is smooth internally and without projections, as the parts 15—22—23 engage edge to edge. Thus at no point within the device are two thicknesses of the sheet metal present in the bottom. By this means no obstructions are presented to retard the movements of the matches. Extending from the flap 23 is a relatively long tongue 24, while a smaller tongue 25 projects from the flap 22 and is provided with a slit 26 to receive the tongue 24 when the receptacle is folded. The shorter slotted tongue 25 overlaps the central narrow portion of the bottom 15, while the longer tongue 24 also overlaps the bottom 15 and is passed through the slit 26 of the shorter tongue 25 and bent over upon itself, thus forming an effectual lock beneath the bottom of the receptacle to firmly unite the parts at the narrow intermediate part of the bottom 15. This arrangement leaves the broader lower portion of the bottom 15 free and unsupported, while at the same time reinforcing and strengthening the central narrow portion. At its lower end the front 10 is provided with a notch 27 corresponding to and located opposite the notch 18 of the bottom 15 when the receptacle is closed, as shown in Fig. 2, and thus 100

providing the means for extracting the matches one at a time, as will be obvious.

The matches are deposited within the receptacle and a number of the matches will be displayed intermediate their ends through the notches 18—27, while the terminals of the matches are supported upon the bottom 15 at the sides of the notch 18. The material of which the device is constructed 10 should possess the requisite degree of resiliency so that the matches when undisturbed will be firmly held in position, while at the same time a single match may be abstracted by the downward force applied 15 causing it to displace the outer portions of the bottom 15 to permit the single match to pass, but preventing more than one match at a time from being abstracted. Formed in the upper portion of the back member 20 are apertures 28 through which the suspending devices, such as nails or hooks will pass to support the "safe" from a wall or other stationary structure. The projecting portion 14 of the "safe" is bent into L- 25 shape and provided with an abrasive substance upon its inner face to serve as a match scratcher. The upper ends of the sides 12—13 are inclined substantially to the same extent as the lower ends and in 30 parallel relation thereto, and form a sloping top. Hingedly united to the back 11 is a cover 29, the cover preferably rolled at its free edge to facilitate opening same.

Located within the casing forming the receptacle for the matches is a follower, preferably of sheet metal and bent into parallel relation whereby sides 30—31 are formed spaced a short distance apart and with a projection 32 at the free edge of the side 35 31, the projection being bent at right angles to the part 31 and soldered or otherwise secured to the free edge of the part 30 and extending beyond the same and forming a flange, as shown. A strip of sheet metal 40 45 33 is soldered or otherwise secured to the bent or "bight" portion of the parts 30—31 and extends beyond the part 31 at the side opposite to the bent portion 32. The two parts 32—33 are designed to bear against 50 the inner faces of the members 10—11 and serve to prevent the united portions 30—31 from tilting when moving downwardly upon the matches, but will maintain a uniform pressure upon the matches and thus prevent 55 them from becoming clogged within the receptacle. The space between parts 30—31 forms an air space to prevent any heat which may arise from the partly burned matches from being communicated to the mass of 60 unburned matches beneath. Formed through the sides 12—13 are openings 34—35 through which the burned matches may be inserted to fall upon the follower. By this means the portion of the casing beneath the

follower holds the unburned matches, while 65 the space above the follower forms a receptacle for the burned matches. The space between the portions 30—31 may be filled with asbestos or any other non-conducting substance or material to increase the safety of 70 the device if preferred. For the purpose of illustration the asbestos is indicated by the character 36. At its upper end the front 10 is extended, as shown at 37, and bent over the upper portion of the front and provided 75 with means for supporting the representation of a coin, preferably a "Lincoln" penny. Formed in the side edges of the upper front portion of the member 10 are longitudinal clefts or slits 38—39, while L-shaped clefts or slits 40—41 are formed in the side edges of the member 10 below the center, thus leaving relatively narrow solid portions 42—43 between the clefts 38—40 on one side and 39—41 at the opposite side. 80 At their ends the slits 38—39 are directed outwardly for a short distance, thus leaving relatively long tongues which may be bent downwardly to form supports for a sheet of paper, represented at 44, upon which advertising matter is placed. At their lower ends the clefts 40—41 are likewise directed outwardly toward the center to form similar tongues to support the lower end of the advertising sheet. By this means the advertising sheet 44 is insertable beneath the tongues formed by the clefts and inserted and removed as required. By this means 85 the sheet may be easily changed when it is desired to change the advertising matter. 90 At its upper end the sheet 44 projects beneath the lower edge of the downwardly turned extension 37, which thus supports the upper end of the advertising sheet. Formed in one of the sides of the casing, for 95 instance, the side 13, are two U-shaped tongues 46—47 in which any suitable article may be supported, for instance, a thermometer 100 48, as shown.

The device may be of any required size, 110 of any suitable material, and ornamented in any desired manner, may be suspended in any convenient location, will support the matches in convenient position for extraction one at a time, will hold the matches in 115 place so long as any matches remain within the receptacle, and will operate effectually until the last match has been abstracted.

Having thus described my invention, what 120 is claimed as new is.

A match safe of the character described formed from a single piece of sheet metal bent to shape and comprising a front, back and sides, a bottom integral with the back and formed with recesses in its side edges 125 and with reduced portion between the recesses, extensions upon the sides and corresponding to and fitting within the recesses

of the bottom with the inner faces of the extensions even with the inner face of the bottom, and means externally of said bottom for uniting said extensions, the portion 5 of said bottom which extends beyond the uniting device of the extensions being unsupported.

In testimony whereof, I affix my signature in presence of two witnesses.

ARTHUR S. DURRUM. [L. S.]
